UNITED STATES PATENT OFFICE.

JOHN BENNER, OF PHILADELPHIA, PENNSYLVANIA, ASSIGNOR TO AMERICAN STOVE AND HOLLOW WARE COMPANY.

DESIGN FOR FIRE-PLACE HEATER.

Specification forming part of Design No. 7,602, dated August 4, 1874; application filed July 20, 1874.
[Term of Patent 7 years.]

To all whom it may concern:

Be it known that I, JOHN BENNER, of the city of Philadelphia, in the county of Philadelphia, and State of Pennsylvania, have invented a Design for Fire-Place Heaters, of which the following is a specification:

The nature of my design is fully represented in the accompanying photographic illustration, to which reference is made.

It consists of carved and open-work figures, arranged upon the exterior of a fire-place heater, which heater is shown in the illustration standing in its natural place for use—that is, half its diameter within the iron or marble archway to the fire-place.

a and b are entirely of open-work, applied to screen the plain surfaces of the heater beneath them. c is a carved border to the heater, and made of vine-like and leaf-like portions of varying widths, so as to fill the space between the heater with its varying diameters, and the iron or marble archway to the fire-place with which it stands in combination. d d are carved figures of wreath-like external form and cross-barred vertically, as shown. The door-frames and frames for mica windows, also the hearth-plate of the heater, all have small carved figures and tracings to complete the artistic effect of the whole design, all of which is so clearly shown in the illustration as not to need further description.

What I claim as my invention is—

1. The design for a fire-place heater herein described and shown, including the border c, by which it is combined with the archway to the fire-place, substantially as shown.

2. The design for a fire-place heater, a b d, with the varied small carved figures and tracings given in the illustration, not including the border c, substantially as shown.

JOHN BENNER.
